CHARLES W. HACK, OF NEW YORK, N. Y.

THERMOSTAT.

1,306,007.

Specification of Letters Patent. Patented June 10, 1919.

Original application filed April 28, 1917, Serial No. 165,072. Divided and this application filed November 1, 1917. Serial No. 109,634.

To all whom it may concern:

Be it known that I, CHARLES W. HACK, a citizen of the United States, and a resident of New York, in the county of New York and State of New York, have invented 5 certain new and useful Improvements in Thermostats, of which the following is a specification.

The invention relates to improvements in 10 thermostats, and particularly to thermostats for use in fire alarm systems and the like. This application is a division of my prior application, Ser. No. 165,072, filed April 28, 1917.

15 The main object of the invention is to provide a thermostat which is not only simple and efficient in operation and construction, but one which is unlikely to get out of order and in which failure of operation is extremely unlikely to occur.

20 Further and more specific objects, features and advantages will more clearly appear from the detailed description given below, taken in connection with the accompanying 25 sheet of drawings, which forms a part of this specification and which illustrates an embodiment of my improvements in one form.

25 In the drawing, Figure 1 illustrates a system employing a thermostat, embodying the invention in one form, certain parts of the system being shown diagrammatically.

30 Fig. 2 is a perspective of the relay drop, certain parts being broken away in order to more clearly illustrate the same;

Fig. 3 is a vertical section of the thermostat;

35 Fig. 4 is a front view of the thermostat; Fig. 5 is a top view of the thermostat with the cap removed;

40 Fig. 6 is a top view of the thermostat with the cap thereon and showing part of the means for securing the thermostat in place;

45 Fig. 7 is a detail, illustrating a modification in the thermostat.

50 Referring to the various figures, 1 represents an air expansion chamber member, consisting primarily of the two parts secured together to form a hollow air cham-

ber, and 2 represents the body part of the thermostat. Chamber 1 carries screw-threaded extension or part 3, which is screw-threaded through a bushing 4, extending through the body 2, but insulated therefrom by an insulating bushing 5. Stretched over the top of the body portion 2 is a diaphragm 6, which normally rests in contact with the top of the screw-threaded spindle 3, as shown in Fig. 3. The part 3 is provided with a duct 4', leading from the air chamber 1 to the point at which the spindle 3 contacts with the diaphragm 6. 7 represents a frame piece extending over the top of the diaphragm 6 and carrying a block of insulating material 8, through which extends a contact screw 9, adapted to make contact with the diaphragm 6 when the latter is raised by expansion of air in the chamber and in the air space beneath the diaphragm 6. A cap 10 is provided for covering the parts, as shown in Fig. 3, this cap being secured to the body portion 2 by screw 11. Secured to this cap is a strip of insulating material 12, carrying three binding posts 13, 14 and 15. A fusible conductor 16 leads from binding post 15 to the bushing 4 and is connected to the latter by means of screw 17, so that the binding post 15 is electrically connected with the contact spindle 3, which normally contacts with the diaphragm 6. The screw 9 is electrically connected with the binding post 14 by means of a conductor 18 extending through an aperture in cap 10. Screws 19 secure the insulating strip 12 to the cap 10, and a conductor 20 connects one of the screws 19 with the binding post 13, so that the binding post 13 is electrically connected with the body portion 2 and diaphragm 6. The body piece 2 is provided with an aperture 21 therethrough, leading to the air space beneath the diaphragm 6, and into this aperture there is screw-threaded a screw 22 having a longitudinal groove 23 and a beveled head, so that the leakage of air from beneath the diaphragm 6 may be regulated by adjusting the position of this screw in the opening 21.

The cover 10 is provided with an opening 24, through which a screw-driver or other

implement may be inserted to adjust the screw 9 to any desired position. Secured to the top of the cap 10 is a bracket 25, which may be screwed to the ceiling of a room or 5 any other position where it is desired to place the thermostat. The bracket 25 is secured to the cap 10 by two screws 26, and, if it is desired to adjust the screw 9, the device may be removed from the ceiling and one of 10 the screws 26 taken out, when bracket 25 may be swung about on the other screw 26, as shown in dotted lines at 28, whereupon the screw-driver may be inserted through the opening 24 to adjust the screw 9.

15 Situated on the insulating piece 12 is a spring device 29, secured thereto by screw 30'. One of the lower ends of this device is formed into a loop of fusible metal, and, should the surrounding temperature rise to 20 a predetermined point, this loop will fuse and the two sides of the device spring outwardly, so as to contact with the binding posts 13 and 14 and form an electrical connection between the two.

25 30 represents an electric bell, or any other suitable alarm signal device, one terminal of which is connected to the binding post 14 by conductor 31. The other terminal is connected to a battery 32, or other source of 30 electrical energy, by means of a conductor 33. The other terminal of the battery 32 is connected to the binding post 13 by conductor 34.

The binding post 15 is connected to one 35 terminal of a relay, the windings of which are indicated at 35, by conductor 36, the other terminal of the windings being connected to the conductor 33 by means of a conductor 37. The coils of the relay 35 are 40 adapted to operate an armature 38, having a contact 39, adapted to make contact with a contact 40 when the coils 35 are deenergized. Contact 40 is connected to one of the binding posts of the bell 30 by a conductor 45 41, and the armature 38 is connected to the conductor 34 by conductor 42.

In operation, should a fire occur in the neighborhood of the thermostat, the air in 50 chamber 1 will expand and cause a rush of air through the duct 4' into the space beneath the diaphragm 6, which will cause the diaphragm 6 to be raised and break the circuit through the coils 35 of the relay, this circuit being as follows:—from battery 32, 55 through conductor 33, conductor 37, windings 35, conductor 36, binding post 15, conductor 16, contact stem 3, diaphragm 6, body portion 2, screw 19, conductor 20, binding post 13, and conductor 34, back to the 60 other side of the battery.

Upon the coils 35 becoming deenergized, the armature 38 makes contact with the contact 40, thereby closing the circuit to cause the operation of the alarm device 30, the lat-

ter circuit being as follows:—from one side 65 of the battery 32, through conductor 33, through the alarm device 30, through conductor 41, contact 40, armature 38 and conductor 42, back to the other side of the battery. Since the duct 4' enters the space beneath the diaphragm 6 directly at the point where the diaphragm 6 contacts with the stem 3, any air forced through the duct more 70 positively separates the diaphragm 6 from the stem 3, so that there is little or no danger 75 of any expansion of air taking place without breaking the circuit as above described.

In order that very gradual rises of temperature may not cause such an alarm,—as a rise in temperature due to summer 80 weather,—compensating screw 22 is provided, so that a slight leakage of air is permitted from the space beneath the diaphragm 6, which leakage, however, is insufficient to prevent the operation of the diaphragm in case a relatively rapid rise in 85 temperature takes place, as would be due to a fire in the neighborhood. In many instances, it is found that this compensating screw is unnecessary, however, because of 90 the slight leakage which occurs about the various parts.

The rising of the diaphragm 6 in the manner described not only causes the operation of the alarm signal by the breaking of the 95 normally closed circuit through the relay, as above described, but the expansion of air also raises the diaphragm 6, so that it will make contact with screw 9, which closes a normally open circuit through the conductors 31 and 34 and alarm device, so that it is 100 doubly assured that the alarm device will be operated. This normally open circuit is as follows:—from one side of the battery 32, through the conductor 33, alarm device 30, 105 conductor 31, binding post 14, conductor 18, screw 9, diaphragm 6, body portion 2, screw 19, conductor 20, binding post 13, and conductor 34, to the other side of the battery. Thus, if there should be any failure of the 110 relay to operate, the alarm signal will be operated in this independent manner.

Should the rise in temperature, for any reason, fail to operate the diaphragm, it will cause the connecting conductor 16 to be 115 fused and thus break the circuit of the normally closed circuit, so that the relay will be operated as before and will cause the operation of the alarm signal in the manner above described.

As a further means of assuring the operation of the alarm signal, if the diaphragm 6 fails to operate, the fusible metal on the end of the device 29 will melt, thereby causing the same to spring apart and short-circuit 125 binding posts 13 and 14, so as to close the circuit between the conductors 31 and 34 and thus close the normally open circuit, which

will bring about the operation of the alarm device in the manner above described.

The relay 35 is preferably in the form of an electrical drop, one form of which is illustrated in Fig. 2, the windings 35 being shown as magnet coils adapted to attract an armature 50 pivoted on a pivot 51 and carrying a contact point 52. Also rigidly secured to the armature and pivot is a disk 53, in front of which is a frame piece 54, having apertures 55, through which the disk 53 may be seen. When the coils 35 are energized, the armature 50 will be attracted upwardly thereto, as shown in Fig. 2, and the disk 53 will have black portions thereon appearing through the apertures 55. When the circuit through the coils 35 is broken, the armature 50, by its weight, will drop about one-quarter of a revolution, until the contact 52 makes contact with a contact member 56, whereupon white portions on the disk 53 will appear through the openings 55.

Contact 56 corresponds with the contact 40 in Fig. 1, and the armature 50 corresponds with the armature 38 in Fig. 1, contact 40 being insulated from the other parts of the device, and being provided with a binding post 57, by means of which the conductor 41 may be suitably connected thereto. The device shown in Fig. 2 is provided with two terminals 58 and 59, by means of which the conductors 36 and 37 may be suitably connected to the windings 35.

Thus, when the normally closed circuit through the coils 35 is broken by the raising of the diaphragm 6 in the manner above described, the armature 50 will fall, causing the drop to show white, which will indicate the presence of a fire, or else that the device is out of order, because, if the normally closed circuit should be broken in any other way, as by accident, the drop shown in Fig. 2 will so indicate, so that the circuit may be repaired at once.

In case a number of arrangements as shown in Fig. 1 be used,—as in various rooms in a hotel or other building,—each thermostat being put in a different location, then each closed circuit will have its own drop, so that the operation of the drop will indicate the particular room or place where the fire or undue rise in temperature has occurred.

In such an arrangement, the various thermostats may be made to cause the same alarm device to operate, or separate alarm devices may be provided for each thermostat, as desired.

In Fig. 7, a modification of expansion chamber is shown. Instead of the expansion chamber being in the form of a hollow shallow container 1, it is in the form of a long piece of tubing 60, which tubing may be extended about the room or formed into coils,

as desired, which coils may be located in different places, so that, no matter where the fire occurs, it will be certain to cause an expansion of air which will operate the diaphragm 6.

In order to prevent persons from tampering with the arrangement, a wire cage 61 may be placed about the thermostat, as illustrated in Fig. 1.

While the improvements have been above described in great detail with respect to one embodiment of the invention, it is not desired to limit the invention to the details so described, as many changes and modifications may well be made without departing from the spirit and scope of the invention in its broader aspects.

What is claimed as new and desired to be secured by Letters Patent is:—

1. A thermostat having an expansion chamber, a diaphragm operated by expansion of fluid in said chamber, a contact member normally making contact with said diaphragm, said contact member having a duct communicating with the expansion chamber at one end and at the other end terminating at the point where the diaphragm makes contact with the contact member, the diaphragm normally acting to substantially close the last mentioned end of said duct. 95

2. A thermostat provided with a body member, a diaphragm carried thereby, an expansion chamber, an electrical contact member adapted to contact with the diaphragm and means connecting the contact member with the expansion chamber, whereby the position of the contact member may be adjusted by movement of the expansion chamber.

3. A thermostat provided with a body member, a diaphragm carried thereby, an expansion chamber, an electrical contact member adapted to contact with the diaphragm and means connecting the contact member with the expansion chamber, whereby the position of the contact member may be adjusted by movement of the expansion chamber, said connecting means being provided with a passageway connecting the expansion chamber with the space adjacent 110 the diaphragm.

4. A thermostat provided with a body member, a diaphragm carried thereby, an expansion chamber, an electrical contact member adapted to contact with the diaphragm and means connecting the contact member with the expansion chamber, whereby the position of the contact member may be adjusted by movement of the expansion chamber, said connecting means being provided with a passageway connecting the expansion chamber with the space adjacent the diaphragm, said passageway terminating at the end of the contact member where it makes contact with the diaphragm. 130

5. A thermostat having an expansion chamber, a diaphragm operated by expansion of fluid in said chamber, a contact member normally making contact with said diaphragm, said contact member being adjustable toward and from the diaphragm and carrying the expansion chamber, whereby the expansion chamber may be used to adjust the said contact member.
- 10 6. A thermostat provided with a body member, a diaphragm carried thereby and an expansion chamber in the form of a bulb, the bulb having a neck leading into the space in the body portion on one side of the diaphragm and into contact therewith.
- 15 7. A thermostat provided with a body piece, a diaphragm carried thereby, and an air expansion chamber member having a part extending through the body member but insulated therefrom, said part making electrical connection with the diaphragm and having a duct leading from the air expansion chamber to the point where it makes electrical connection with the diaphragm.
- 20 8. A thermostat provided with a diaphragm, means forming a chamber at one side of said diaphragm, a contact member normally contacting with the diaphragm on the chamber side thereof, and an air expansion chamber connected with said first-mentioned chamber by a duct through said contact member.
- 25 9. A thermostat provided with a diaphragm, means forming a chamber at one side of said diaphragm, a contact member normally contacting with the diaphragm on the chamber side thereof, and an air expansion chamber connected with said first-mentioned chamber by a duct through said contact member and entering the first chamber where the contact member engages the diaphragm, said contact member and said diaphragm forming terminals of a normally closed circuit, whereby upon expansion of air in the expansion chamber the diaphragm is forced away from the contact member to open the normally closed circuit.
- 30 10. A thermostat provided with a diaphragm, means forming a chamber at one side of said diaphragm, a contact member normally contacting with the diaphragm on the chamber side thereof, an air expansion chamber connected with said first-mentioned chamber by a duct through said contact member, and a contact member on the opposite side of the diaphragm.
- 35 11. A thermostat provided with a diaphragm, means forming a chamber at one side of said diaphragm, a contact member normally contacting with the diaphragm on the chamber side thereof, an air expansion chamber connected with said first-mentioned chamber by a duct through said contact member and entering the first chamber

where the contact member engages the diaphragm, said contact member and said diaphragm forming terminals of a normally closed circuit, whereby upon expansion of air in the expansion chamber the diaphragm is forced away from the contact member to open the normally closed circuit, and a contact member on the opposite side of the diaphragm forming a terminal of a normally open circuit, whereby upon said expansion of air in the expansion chamber said normally open circuit is closed.

12. A thermostat provided with a body member, a diaphragm carried thereby, an expansion chamber member having a part screwthreaded through the body member into contact with the diaphragm, means carrying a contact member on the other side of the diaphragm, a cap covering said last-mentioned means, and means securing the device in position.

13. A thermostat provided with a body member, a diaphragm carried thereby, and an expansion chamber member having a part screwthreaded through the body member into contact with the diaphragm.

14. A thermostat provided with a body member, a diaphragm carried thereby, an expansion chamber member having a part screwthreaded through the body member into contact with the diaphragm, means carrying a contact member on the other side of the diaphragm, and a cap covering said last-mentioned means, said cap having an aperture therein to permit of access to said last-mentioned contact member for adjustment thereof.

15. A thermostat provided with a body member, a diaphragm carried thereby, a contact member extending through the body member into contact with the diaphragm, a contact member carried on the other side of the diaphragm, an air expansion chamber connected by a duct with the space on the side of the diaphragm on which the first contact member is located, said duct leading into said space adjacent the point where the first contact member contacts with the diaphragm, three electric terminals carried by the body member, one of which is electrically connected to the diaphragm through the body member, means electrically connecting another to the first-mentioned contact member, and means electrically connecting the third to the other contact member.

16. A thermostat provided with a body member, a diaphragm carried thereby and an air expansion chamber operatively associated therewith, a contact device also operatively associated with the diaphragm, a cover for the latter, and means for securing the latter to any desired place, said cover having an aperture to permit of adjustment

of the contact device, and said aperture being normally covered by said securing means.

17. A thermostat provided with a body piece, a diaphragm carried thereby, an expansion chamber adjustable with respect to said body piece, a contact member extending through the body piece into contact with the diaphragm and adjustably carried with said expansion chamber.
- 10 18. A thermostat provided with a dia-

phragm, an electric contact member coöperating therewith, and a fluid expansion chamber carried by said contact member and communicating with the space on one side of the diaphragm by a duct through said contact member. 15

Signed at New York in the county of New York and State of New York this 30th day of October A. D. 1917.
